RECLOSABLE CARTONS

William R. Saidel, Park Forest, Ill., assignor to Foil Cartons, Inc., Chicago Heights, Ill., a corporation of Illinois

Application November 13, 1956, Serial No. 621,694

6 Claims. (Cl. 229—17)

The present invention relates to cartons and more particularly to cartons which can be initially sealed, opened to permit removal of part of the contents and then reclosed to assist in maintaining the remainder of the contents in a relatively sealed condition within the carton until the removal of more of the contents is desired.

The invention also comprises structure wherein a single blank can be precut, perforated and scored so that it may be readily folded, as necessary, to form the carton.

The particular feature of the invention relates to a construction of such a nature that when the carton has been set up and sealed it may be readily opened to expose a portion of the carton for the removal of some of the contents and then reclosed in a simple, easy and effective manner.

Cartons of this general construction have been heretofore proposed but they are open to one or more objections which it is the object of the present invention to overcome.

Referring to the drawings which illustrate a preferred embodiment of the invention,

Fig. 1 is a face view of a carton blank, from which the carton can be erected or set up;

Fig. 2 is a perspective view of a carton partially set up;

Fig. 3 is a perspective view of a fragmentary part of the steps in closing the carton opening;

Fig. 4 is a view similar to Fig. 3 but showing the carton fully closed, and

Fig. 5 is a sectional view on the line 5—5 of Fig. 4.

As shown in Fig. 1, the carton comprises a single piece of box or container board having body forming panels 10, 11, 12, 13 and 14. The panel 10 has attached thereto flaps 10T and 10B separated by the score lines 10' and 10''.

Panel 11 has affixed thereto flaps 11T and 11T' and 11B, being defined by the score line 11' and 11'' and the perforated line 11P.

Panel 12 has attached thereto a relatively long flap 12T and a relatively short flap 12B, being foldable along the lines 12' and 12'' respectively.

Panel 13 has affixed thereto flaps 13T and 13T', the latter being foldable along the perforated line 13P and the former along the score line 13'. At the bottom there is a flap 13B foldable along score line 13''.

Panel 14 includes flaps 14T and 14B respectively, folded along score lines 14' and 14'' respectively.

The carton blank is further foldable along the score lines 15, 16, 17 and 18.

In the set up of the carton certain of the flaps are intended to be adhered, one to the other. For illustrative purposes the surfaces to which other parts are to adhere have been illustrated by means of stippling, as best appears in Fig. 1.

The carton may be set up by folding panels 11 and 13 along the score lines 16 and 17 until panels 11

2

and 13 are in parallel relation, then folding panel with its flaps 10T and 10B at right angles to 11, folding panel 14 and its attached flaps 14T and 14B over panel 10 and the flaps 10T and 10B. These parts can then be sealingly united. Thereafter flaps 10B, 14B and 12B may be folded inwardly, flap 11B folded thereover and then 13B folded on top of 11T, in which condition the parts are sealingly united.

As a matter of convenient reference that part of the 10 carton comprising the portions 11B and 13B in the set-up carton, will be termed the bottom and the part comprising the portions 11T and 13T and associated portions termed the top.

To form the top of the carton adhered flaps 10T and 14T are folded inwardly, flap 13T folded on top of 11T. Thereafter flap 12T is folded inwardly so that the end portion 12F thereof overlies part 13T. Then flap 13T is folded over flap 12T. Finally flap 11T' is folded over flap 13T'. All of the engaging flaps are then sealingly united except only that portion 12F of flap 12T which extends inwardly of the carton beyond the underlying zone 13A of flap 13T.

Thus while flap 12T is sealingly united with flap 13T and flap 13T' an end portion 12F of the flap 12T is free 25 from sealing engagement with the underlying flap 13T.

It will thus be seen that the carton is effectively sealed throughout. Yet, when it is desired to open the carton, it is but necessary to pull upwardly on the free end portion 12F whereupon flaps 13T' and 11T', which overlie flap 12T, will be torn from the panels 13 and 11 respectively along the perforation lines 13P and 11P respectively, thus exposing the rectangular opening 20 through which part or all of the contents can be removed. However, the carton is intended for use with 35 products, portions only of which will be removed from time to time.

To reclose the carton the end portion 12F of flap 12T is tucked under the inner face of flap 11T as shown by dotted lines in Fig. 5. In closed position end portions 40 of flaps 11T' and 13T' form a shoulder 22 which abuts against shoulder 23 formed by the ends of flaps 11T and 13T. A neat, compact and relatively tight closure is thus formed. When it is desired to remove additional contents from the carton the closed structure comprising the sealingly engaged flaps 12T, 13T' and 11T' may 45 easily be swung upwardly with the score line 12' as the hinge, the desired amount of the contents removed and the carton opening again closed, as before described.

The lift flap 12T is provided with score lines in the 50 shape of an inverted Y. This is to facilitate folding the lift flap downwardly from the position shown in Fig. 2 to that of Fig. 3 without catching on the edges of flaps 11T' and 13T'. To fold the lift flap pressure is applied against the triangular area 12A which tends to cause the 55 flap to assume a somewhat concave shape, thus slightly reducing its width so that it will swing freely past the upstanding flaps 11T' and 13T'.

The terms "top" and "bottom" in the specification and claims are used merely as a matter of convenience in 60 description and are not intended as limitations since other parts of the carton, where like structural arrangements can be provided, are intended to be within the scope of the invention disclosed and claimed.

I claim:

1. A carton comprising a bottom, two side walls, two 65 end walls, a permanent top closure section extending from an end wall inwardly and terminating short of the other end wall to provide an access opening, a lift flap foldably connected to said last mentioned end wall extending over said opening to close same and having an end portion extending beyond the opening and resting upon a portion of said permanent top closure adjacent

said opening, and a pair of flaps, one connected to each side wall by a weakened fold line to facilitate severance, one of said last mentioned flaps being folded upon the upper side of said lift flap and being sealingly united thereto and the other of said last mentioned flaps being folded upon the upper side of the said flap which is disposed upon the lift flap and being sealingly united thereto, whereby said opening is initially sealingly closed in such manner that when the lift flap is initially swung upwardly on its fold line, said pair of flaps is severed from the side walls along said weakened fold lines, thus exposing the access opening and also permitting re-closing of the access opening by folding the lift flap downwardly and inserting an end portion thereof under the adjacent permanent top closure section.

2. The structure set forth in claim 1 in which at least one of the pair of flaps overlying said lift flap has an edge portion which is in substantial alignment with that edge portion of the permanent top closure section which terminates short of said other end wall whereby when the end portion of the lift flap is inserted under the permanent top section, said aligned edge portions of said overlying flap form a shoulder which abuts against the shoulder formed by the adjacent end of the said permanent top section.

3. The structure set forth in claim 1 in which said pair of flaps which overlie said lift flap have edge portions which are in substantial alignment with that edge portion of the permanent top closure section which terminates short of said other end wall whereby when the end portion of said lift flap is inserted under the permanent top section, said aligned edge portions of said overlying flaps form a shoulder which abuts against the shoulder formed by the adjacent end of said permanent top section.

4. The arrangement set forth in claim 1 in which the lift flap includes score means so disposed that pressure applied to an outer face portion of the lift flap results in curving the lift flap to reduce its width at least in part so that it may be folded between the pair of side flaps without catching on the edges thereof.

5. The arrangement set forth in claim 1 in which the lift flap comprises score lines which prior to the folding of the lift flap to closing position are of inverted Y

shape, the stem portion extending along a median plane of the flap and terminating short of the fold line of the flap with its end wall and the branch lines of the Y extend angularly toward opposite edges of the lift flap.

5 6. A carton comprising a bottom, two side walls, two end walls, a permanent top closure section extending from an end wall inwardly and terminating short of the other end wall to provide an access opening, a lift flap foldably connected to said last mentioned end wall extending over said opening to close same and having an end portion extending beyond the opening and resting upon a portion of said permanent top closure adjacent said opening and being sealingly united thereto in part and having an end portion unsealed to facilitate the initial lifting thereof, and a pair of flaps, one connected to each side wall by a weakened fold line to facilitate severance, one of said last mentioned flaps being folded upon the upper side of said lift flap and being sealingly united thereto and the other of said last mentioned flaps being folded upon the upper side of the said flap which is disposed upon the lift flap and being sealingly united thereto, whereby said opening is initially sealingly closed in such manner that when the lift flap is initially swung upwardly on its fold line, said pair of flaps is severed from the side walls along said weakened fold lines, thus exposing the access opening and also permitting re-closing of the access opening by folding the lift flap downwardly and inserting an end portion thereof under the adjacent permanent top closure section.
